UNITED STATES PATENT OFFICE.

PARK D. FOLKES, OF HAYS' LANDING, MISSISSIPPI.

HOE-SHARPENER.

SPECIFICATION forming part of Letters Patent No. 339,398, dated April 6, 1886.

Application filed June 19, 1885. Serial No. 169,237. (No model.)

To all whom it may concern:

Be it known that I, PARK D. FOLKES, of Hays' Landing, in the county of Issaquena and State of Mississippi, have invented a new and Improved Hoe-Sharpener, of which the following is a full, clear, and exact description.

My invention relates to implements designed particularly for sharpening the blades of hoes, but useful also for giving an edge to axes, mowing-machine knives, or other cutting-tools, and has for its object to facilitate the sharpening operations and enable them to be performed with greater accuracy and at a largely reduced cost compared with the use of files.

The invention consists in certain novel features of construction and combinations of parts of the sharpener, all as hereinafter fully described and claimed.

Reference is to be had to the accompanying drawings, forming part of this specification, in which similar letters of reference indicate corresponding parts in both the figures.

Figure 1 is a perspective view of the hoe-sharpener as in use on a hoe, and Fig. 2 is a side elevation thereof.

The letters A B indicate two lever-bars, which are pivoted together on a pin, C, and back of the pivot are formed with handles a b, respectively, and forward of the pivot take the shape of long jaws, the implement in general appearance somewhat resembling a pair of ordinary shears.

In the jaw A' of lever-bar A is held, preferably by a set-screw, d, a whetstone or sharpener, D, which may be of any suitable kind or grade of fineness, according to the tool or implement or cutter it is to be used for sharpening, and in the end of the jaw B' of lever-bar B is pivoted, on a pin, e, the roller or anti-friction wheel E, the periphery of which projects beyond the end of the bar, which preferably is turned upward, as clearly shown in Fig. 2.

In using the sharpener on a hoe-blade, for instance, the jaws A' B' will be opened so that the whetstone D will rest on the blade F of the hoe at an angle with one face

of the blade, while the anti-friction roller E rests against the other face of the blade, as shown, and by holding the handles a b of the implement in one hand while the other hand holds the hoe the sharpener may be moved lengthwise to carry the whetstone D back and forth over the edge of the hoe-blade to give it a clean sharp edge.

The sharpener may be used either jaw up-
permost for sharpening the hoe-blade all from
one side or face or from both faces, as may be
desired.

The roller E is not essential to the success-
ful working of the implement; but it greatly
facilitates the sharpening operation, as its
rolling contact reduces the friction on the
hoe-blade face to a minimum, and enables the
operator to much more easily control the po-
sition of the whetstone on the blade to pre-
sent the stone square across the edge of the
tool or at any desired angle to either side. 70

It is evident that the sharpener may be used
to advantage for giving an edge to a large
variety of tools—axes, for instance—and also
may be used to sharpen mowing-machine
knives without removing them from the ma- 75
chine.

The whetstone D may readily be turned in
the jaw A' to present any one of its faces to
the work, and may be replaced quickly by a
new stone when worn out or when broken by
accident.

The bars A B need not necessarily be pro-
vided with handle portions a b back of the
pivot, as the jaws A' B' may be held closed
on the blade or cutter to be sharpened by
direct pressure of the hand; but the construc-
tion with handles is preferred.

The sharpener, as a simple, inexpensive,
and effective implement, is intended to take
the place of files, which are costly and unsat- 90
isfactory in use for the purposes specified.

Having thus fully described my invention,
I claim as new and desire to secure by Letters
Patent—

1. A sharpening implement comprising a 95
pair of jaws pivoted together, a whetstone
or sharpening device secured along the inner
edge of one jaw, and an anti-friction roller

journaled on the other jaw, substantially as herein set forth.

2. A sharpening implement comprising a pair of lever-bars, A B, pivoted together at C, and provided with extensions back of the pivot, forming handles *a b*, and with forward jaws, A' B', a whetstone or sharpening de-

vice, D, secured in jaw A', and an anti-friction roller, E, journaled on jaw B', substantially as herein set forth.

PARK D. FOLKES.
